TOY GOLFER

Kenneth C. Woodrey, 2305 Erie Ave., Middletown, Ohio

Filed Mar. 11, 1960, Ser. No. 14,434

4 Claims. (Cl. 46—245)

This invention relates to toys, and more particularly to a toy in the form of a mechanical golf player.

A main object of the invention is to provide a novel and improved mechanical toy in the form of a golf player, the toy being simple in construction, being easy to operate, and providing a close simulation to the actual body movements performed by a golf player in striking a golf ball.

A further object of the invention is to provide an improved toy in the form of an electrically operated mechanical golf player, the toy being relatively inexpensive to manufacture, being sturdy in construction, and being usable for playing a simulated game of golf on any suitable surface, for example, indoors upon a rug or carpet simulating a golf course, or outdoors in any suitable area.

Further objects and advantages of the invention will become apparent from the following description and claims, and from the accompanying drawings, wherein:

Figure 1 is a top plan view of a golfing toy constructed in accordance with the present invention.

Figure 2 is a front elevational view, partly in vertical cross section, of the simulated golf player of Figure 1, said view being taken on the line 2—2 of Figure 1.

Figure 3 is an enlarged vertical cross sectional view taken substantially on the line 3—3 of Figure 1.

Figure 4 is a cross sectional view taken substantially on the line 4—4 of Figure 3.

Figure 5 is a cross sectional view taken substantially on the line 5—5 of Figure 3.

Figure 6 is a cross sectional view taken substantially on the line 6—6 of Figure 3.

Figure 7 is a cross sectional view taken substantially on the line 7—7 of Figure 3.

Figure 8 is an enlarged cross sectional detail view taken substantially on the line 8—8 of Figure 2.

Figure 9 is an enlarged fragmentary perspective view of the shank end portion of a golf club which may be employed with the toy of Figure 1.

Referring to the drawings, 11 generally designates a toy golfer constructed in accordance with the present invention. The toy golfer 11 comprises a hollow base 12, which may be generally rectangular in form, or which may have any other suitable shape, the base 12 defining a housing in which is mounted an electric motor 13 adapted to be energized at times by a pair of flashlight batteries 14, 14 mounted in the base 12 adjacent the motor 13, as is clearly shown in Figure 2. A control switch 15 is mounted in the base 12 at one end thereof, the switch 15 being provided with the externally projecting control button 16 which is accessible from the outside of the base to control the motor 13. The motor 13 is connected to the batteries 14, 14 in a circuit which includes the control switch 15.

Designated generally at 17 is an upstanding shaft member which is provided with the base portion 18. Base member 18 is fastened to the top wall of the hollow supporting base 12 by a rivet 19 which is located adjacent one side edge of the base member 18. A flexible cable 20 extends upwardly through the top wall of the hollow sup-

2

porting member 12 and the portion of base member 18 located adjacent the opposite side edge of said base member, as shown in Figure 3. The upstanding shaft member 17 is provided with the inclined top portion 21 which is directed upwardly and forwardly.

Secured on the support member 17 and the lower portion of the inclined shaft element 21 is a hollow member 23 shaped to simulate the lower portion of the body of a toy golfer, the hollow member 23 being thus rigidly held. Designated at 24 is a body shaped to simulate the head of the toy golfer, said body being secured to the top end of the inclined upper shaft portion 21, being engaged on said top end and being clamped thereto by a set screw 25 provided in the simulated head portion 24.

Designated at 26 is a simulated torso element which is rotatably mounted on the inclined shaft portion 21 between the stationary body portion 23 and the stationary head portion 24. The simulated torso member 26 is provided with the simulated, forwardly extending arms 27, 27 which are joined together at 28, as shown in Figure 8, and which are formed at their junction 28 with a squared socket 29 in which the squared end 30 of a simulated golf club 31 is lockingly receivable. Thus, as shown in Figure 9, the shank of the golf club 31 terminates in the reduced squared portion 30, and the end of the squared portion 30 is formed with a dovetail element 32 which is lockingly receivable in the upper end of the socket 29 and which is yieldably held in the socket by a resilient ring 33 provided in an annular recess 34 formed in the top end portion of socket 29. By exerting manual outward force on the shank of the golf club 31, the squared portion 30 thereof may be disengaged from the socket 29, allowing a different golf club to be substituted. As will be readily apparent, the clubs may have striking heads 35 of different pitch, so that a simulated golf ball, shown at 36, will travel in different paths in accordance with the angular inclination of the head 35 of the golf club employed when the head strikes the ball.

A simulated tee 37 is provided on the top wall of the supporting base 12, and the simulated ball 36 may be positioned on the tee in the path of travel of the golf club head 35 so that the ball will be struck when the golf club swings downwardly, in a manner presently to be described.

The simulated torso 26 is provided in its upper portion with a wall element 38 through which the inclined supporting shaft member 21 rotatably extends. A biasing spring 39 of generally spiral shape has its outer end portion engaged with an anchor pin 40 secured to and depending from the wall 38, and is secured at its inner end to the inclined shaft element 21, as by being engaged with an anchor lug 41 provided on the shaft element 21 in the manner illustrated in Figures 3 and 4. The spiral spring 39 biases the torso member 26 to the starting position defined by a stop arm 42 secured to the inclined shaft portion 21 and engaged by a coiled buffer spring 43 secured to an inwardly projecting lug 44 provided in the intermediate portion of the torso member 26. As shown in Figure 5, the buffer spring 43 is of substantial length, whereby the torso member 26 may rotate in a counterclockwise direction, as viewed in Figure 5, compressing the spring 43, so that when the spring expands it will return the torso member 26 to a position wherein the spring 43 is no longer under compression, namely, to a starting position such as that illustrated in Figures 1 and 2 wherein the golf club 31 is positioned with its head 35 behind the tee 27 but closely adjacent thereto.

Secured in the bottom portion of the simulated torso 26 is a wall member 45 formed adjacent its rim with an arcuate slot 46, which is concentric with the shaft portion 21.

Designated at 47 is a bearing bracket which is secured to the inclined supporting shaft element 21 below the torso member 26 and which is provided with an arm portion 48 in which is journaled a pinion shaft 49 provided with the pinion gear element 50. The flexible shaft 20 is drivingly connected by means of a sleeve coupling 51 to the pinion shaft 49. The shaft of the motor 13 is drivingly connected to the flexible shaft 20 through a conventional gear reduction unit 54 mounted in the hollow supporting base 12 adjacent the motor 13.

Designated at 55 is a driving sleeve member which is rotatably mounted on the inclined shaft portion 21 and which is formed at its lower end with a gear 56 rotatably supported on the bracket member 47. The gear 56 is meshingly engaged by the pinion gear element 50, so that torque is transmitted from the flexible shaft 20 to the driving sleeve 55 through the pinion gear element 50 and the relatively larger gear 56. A clutch plate 57 surrounds the sleeve member 55, being slidably axially thereon, and being connected to a top flange 58 provided on the sleeve 55 by a plurality of coupling pins 59 secured to the flange 58 and extending through apertures 60' formed in the plate 57. Coiled springs 60 surround the pins 59 and bear between the plate member 57 and washers 61 secured to the lower end portions of the pins 59, biasing the plate 57 upwardly, namely, against the flange 58, but allowing the plate 57 to be moved downwardly. An upstanding pin member 62 is formed on the end of an outwardly projecting arm 63 provided on the plate 57, the pin member 62 being engageable in the arcuate slot 46 as the plate 57 rotates in a counterclockwise direction, as viewed in Figure 6, whereby the pin member 62 may transmit torque to the simulated torso 26 to swing said simulated torso in a counterclockwise direction, as viewed in Figure 6 because of the driving engagement of the pin 62 with the upper end 68 of slot 46, as viewed in Figure 6.

Designated at 69 is a generally circular cam member which is secured to the inclined shaft element 21 between the torso member 26 and the flange 53 of sleeve 55, the cam member 69 having a riser portion 70 which is concentric with the inclined shaft member 21 and which increases in thickness in a counterclockwise direction, as viewed in Figure 6, being located in the path of movement of the arm 63. The thickened portion 70 gradually increases in thickness, eventually being of sufficient thickness to move the drive plate 57 downwardly sufficiently to disengage the pin 62 from slot 46 as disc member 57 rotates in a counterclockwise direction, as viewed in Figure 6, thus releasing the simulated torso member 26 from driving engagement by the member 57. When the arm 63 passes beyond the thickened portion 70 of the cam member 69, rotating in a counterclockwise direction, as viewed in Figure 6, the disc member 57 is released and the springs 60 move the disc member 57 upwardly, causing the pin element 62 to engage the bottom surface of the wall 45 until the pin element 62 may enter the lower end of the slot 46, as viewed in Figure 6.

In operation, when the motor 13 is energized, the flexible cable 20 transmits torque through the meshing gears 50 and 56 to the sleeve 55, in turn causing the driving disc member 57 to rotate in a counterclockwise direction, as viewed in Figure 6. The pin 62 enters the slot 46 and drivingly engages with the upper edge 68 of the slot, rotating the torso member 26 in a clockwise direction, as viewed in Figure 1. This initiates the "back-swing" movement of the simulated arms 26 of the toy golfer.

When the arm 63 moves along the thickened cam portion 70, the pin member 62 is retracted from the slot 46, releasing the torso member 26, whereby the spiral spring 39 causes the torso member 26 to be rapidly swung in a clockwise direction, as viewed in Figure 6, and in a counterclockwise direction, as viewed in Figure 1, bringing the head of the golf club 35 against the simulated golf ball 36 and causing the club head to strike the ball

with considerable impact. The cushioning spring 43 allows the club 31 to move past its starting position, thus completing the "down-swing" movement of the club. The cushioning spring 43 then expands, returning the golf club 31 to its normal or starting position, namely the position thereof shown in Figures 1 and 2.

It will be understood that the above cycle of events occurs as a result of energizing the motor 13 for a sufficient period of time to move the driving pin 62 through 10 a sufficient arc to cause the arm 63 to retract the pin from the slot 46. The above described cycle of events may be repeated by again energizing the motor 13, by means of the control switch 15, to cause the disc member 57 to rotate sufficiently in a counterclockwise direction, as viewed in Figure 6, to reproduce the above described events.

The amount of permissive forward movement of the golf club 31 on the "down-swing" may be regulated by 20 adjusting the position of the stop arm 42. For this purpose, the collar portion 80 of the stop arm 42 is provided with a set screw 81 which is engageable with the shaft portion 21 to lock the stop arm 42 in a selected position.

The cam member 69 is provided with a central boss 25 84 which projects upwardly through a central aperture provided in the bottom wall 45 of the simulated torso member 26, a fastening pin 85 extending through the boss 84 and the inclined shaft portion 21 to rigidly secure the cam member 69 to said shaft portion, while at the same time providing a bearing support for the simulated torso element 26.

While a specific embodiment of a toy golfer has been disclosed in the foregoing description, it will be understood that various modifications within the spirit of the 35 invention may occur to those skilled in the art. Therefore, it is intended that no limitations be placed on the invention except as defined by the scope of the appended claims.

What is claimed is:

40 1. A toy golfer comprising a base, an electric motor mounted in said base, an upstanding supporting shaft rigidly secured to said base, a torso element rotatably mounted on said supporting shaft, a simulated golf club secured to and extending outwardly from said torso element, a driving member rotatably and slidably mounted on said shaft adjacent and drivingly engageable with said torso element, first spring means biasing said torso element toward a starting position, means coupling said motor to said driving member to rotate the driving member continuously while the motor is energized, second spring means biasing said driving member toward driving engagement with said torso element, and cam means secured to the shaft adjacent said driving member and constructed and arranged to move said driving member out of driving engagement with said torso element responsive to rotation of said torso element to a predetermined angle beyond said starting position, whereby to release said torso element for return rotation to said starting position.

60 2. A toy golfer comprising a base, an electric motor mounted in said base, an upstanding supporting shaft rigidly secured to said base, a torso element rotatably mounted on said supporting shaft, a simulated golf club secured to and extending outwardly from said torso element, a driving member rotatably and slidably mounted on said shaft adjacent and drivingly engageable with said torso element, first spring means biasing said torso element toward a starting position, means coupling said motor to said driving member to rotate the driving member continuously while the motor is energized, second spring means biasing said driving member toward driving engagement with said torso element, and a cam member secured to and extending partially around the shaft adjacent said driving member, said cam member increasing 65 in thickness in the direction of rotation of said torso

element sufficiently to move said driving member out of driving engagement with said torso element responsive to rotation of said torso element through a predetermined angle beyond said starting position, whereby to release said torso element for return rotation to said starting position.

3. A toy golfer comprising a base, an electric motor mounted in said base, an upstanding supporting shaft rigidly secured to said base, a torso element rotatably mounted on said supporting shaft, a simulated golf club secured to and extending outwardly from said torso element, a driving member rotatably and slidably mounted on said shaft subjacent said torso element, upstanding pin means on the driving member drivingly engageable with said torso element, said torso element being formed with an aperture receiving said pin means, first spring means biasing said torso element toward a starting position, means coupling said motor to said driving member to rotate the driving member continuously while the motor is energized, second spring means biasing said driving member toward driving engagement with said torso element, and a cam member secured to and extending partially around the shaft between the torso element and the driving member, said cam member increasing in thickness in the direction of rotation of said torso element sufficiently to move said driving member downwardly out of driving engagement with said aperture responsive to rotation of said torso element to a predetermined angle beyond said starting position, whereby to release said torso element for return rotation to said starting position.

4. A toy golfer comprising a base, an electric motor mounted in said base, an upstanding supporting shaft rigidly secured to said base, a torso element rotatably

mounted on said supporting shaft, a simulated golf club secured to and extending outwardly from said torso element, a driving member rotatably and slidably mounted on said shaft subjacent said torso element, upstanding pin means on the driving member drivingly engageable with said torso element, said torso element being formed with an aperture receiving said pin means, first spring means biasing said torso element toward a starting position, means coupling said motor to said driving member to rotate the driving member continuously while the motor is energized, second spring means biasing said driving member toward driving engagement with said torso element, a cam member secured to and extending partially around the shaft between the torso element and the driving member, said cam member increasing in thickness in the direction of rotation of said torso element sufficiently to move said driving member downwardly out of driving engagement with said aperture responsive to rotation of said torso element through a predetermined angle beyond said starting position, whereby to release said torso element for return rotation to said starting position, a stop arm secured to said shaft, and yieldable resilient buffer means on said torso element engageable with said stop arm when the torso element rotates back toward said starting position thereof subsequent to the disengagement of said upstanding pin means from said aperture.
